US0D1025762S

(12) **United States Design Patent** (10) **Patent No.:** **US D1,025,762 S**
(45) **Date of Patent:** **** May 7, 2024**

(54) **PICTURE HANGING TOOL**

(71) Applicant: **Shenzhen Yuanshixin Trade Co., Ltd.**,
Shenzhen (CN)

(72) Inventor: **Guosen Liu**, Shenzhen (CN)

(73) Assignee: **Shenzhen Yuanshixin Trade Co., Ltd.**,
Shenzhen (CN)

(**) Term: **15 Years**

(21) Appl. No.: **29/913,445**

(22) Filed: **Oct. 2, 2023**

(51) LOC (14) Cl. **08-11**

(52) U.S. Cl.

USPC **D8/373**

(57) **CLAIM**

The ornamental design for a picture hanging tool, as shown and described.

DESCRIPTION

FIG. 1 is a front perspective view of a picture hanging tool, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an exploded front perspective view of FIG. 1; and, FIG. 10 is an enlarged detail view of area 10 in FIG. 1.

The dash-dot broken lines are for purposes of annotating the enlarged view only and form no part of the claimed design.

1 Claim, 10 Drawing Sheets
